[57] CLAIM

The ornamental design of a compact fluorescent lamp, as shown and described.

DESCRIPTION

FIG. 1 is a front elevational view showing the design of my compact fluorescent lamp, with the broken line showing for illustrative purposes only and forming no part of the claimed design;

FIG. 2 is a right side elevation view thereof, the left side being a mirror image;

FIG. 3 is a bottom isometric view thereof, with the broken line of the lamp connector shown for illustrative purposes only and forming no part of the claimed design;

FIG. 4 is a top view thereof; and,

FIG. 5 is a prospective view from the front, top and left side.
